US00D461555S

(12) **United States Design Patent** (10) Patent No.: **US D461,555 S**
 Binet et al. (45) Date of Patent: **** Aug. 13, 2002**

(54) **SAFETY SYRINGE**

(76) Inventors: **Jean Marc Binet; Benoit Steimer; Armando Lourenco**, all of 1, rue de l'Abbaye, 76960 Notre Dame de Bondeville (FR)

(**) Term: **14 Years**

(21) Appl. No.: **29/127,821**

(22) Filed: **Aug. 11, 2000**

(30) **Foreign Application Priority Data**

May 25, 2000 (FR) 00 3134

(51) LOC (7) Cl. **24-02**

(52) U.S. Cl. **D24/114**

(58) Field of Search D243/114, 112, D243/113; 604/135, 134, 136, 219, 218, 208, 198, 337, 187, 207, 211, 232

(57) **CLAIM**

We claim the ornamental design for the safety syringe, as shown and described.

DESCRIPTION

FIG. 1 is a top perspective view of the new ornamental safety syringe of the present invention.

FIG. 2 is a top plan view thereof.

FIG. 3 is a side elevational view thereof.

FIG. 4 is an exploded perspective view thereof, with the plunger depressed and the protective covers removed for operation.

FIG. 5 is an enlarged perspective view of the front portion of FIG. 1.

FIG. 6 is an enlarged perspective view of the rear portion of FIG. 1; and,

FIG. 7 is an enlarged perspective view of the plunger portion, with the cover removed.

1 Claim, 6 Drawing Sheets
